UNITED STATES PATENT OFFICE.

JAMES M. EDWARDS, OF AUDUBON, IOWA.

CAR-COUPLING.

SPECIFICATION forming part of Letters Patent No. 339,751, dated April 13, 1886.

Application filed February 13, 1886. Serial No. 191,845. (No model.)

To all whom it may concern:

Be it known that I, JAMES M. EDWARDS, a citizen of the United States, residing at Audubon, in the county of Audubon and State of Iowa, have invented certain new and useful Improvements in Car-Couplings; and I do hereby declare that the following is a full, clear, and exact description of the same, reference being had to the annexed drawings, making a part of this specification, and to the letters and figures of reference marked thereon.

Figure 1 of the drawings is a perspective view of a draw-head of a railroad-car provided with my improved coupling, showing the coupling-pin elevated and the supports for the coupling-link closed down against and seated in a recess in the end of the draw-head to couple with the opposing draw-head; Fig. 2, a similar view of the opposing draw-head with the link in position for coupling and supported by the arms which are extended for the purpose; Fig. 3, a longitudinal section of the two draw-heads as above described, and Fig. 4 a horizontal section through one of the draw-heads.

The present invention has relation to certain new and useful improvements in automatic car-couplers, and has reference to that class in which the coupling-pin is held in an elevated position ready for coupling, and released by a tripping device operated by the two draw-heads when coming together; and the invention consists in the details of construction, substantially as shown in the drawings and hereinafter described and claimed.

In the accompanying drawings, A B represent the opposing draw-heads of a railroad-car, provided at its front end with a recess, *a*, in which are seated the link-supporting arms C. These arms are curved, as shown, and connected together by a pin, *b*, on the end of one arm entering an elongated slot, *c*, in the other, and the shanks *d* of said arms, which extend along the sides of the draw-head, pass through eyes *e*, which support them and form guides for the shanks when the arms are extended to support the coupling-link D' in a horizontal position.

The shanks *d* are provided with keys *f*, and the sides of the draw-heads have L-shaped

slots *g*, in which work the keys of the shanks, the arms C, when closed down in the recess *a*, to come flush with the end of the draw-head, bringing the keys in position in the rear end 55 or upright portion of the L-shaped slots, thereby locking the link-supporting arms in their closed position.

When it is desired to extend the arms C for supporting the link D, the arms are slightly 60 elevated at their point of connection, the elongated slot *c* admitting of this movement, and at the same time the shanks *d* are turned sufficiently to bring the keys *f* in line with the horizontal portion of the L-shaped slots *g*, thus 65 enabling the shanks and arms to be drawn out as required, stops *h* being provided at the forward extremity of the slots, against which the keys abut, to prevent the arms from being drawn too far out. The coupling-pin E passes 70 through a hole in the front end of an arm, F, curved, as shown, to form a seat for the head of the pin, and the rear end of the arm is pivoted to ears or lugs *i* on the draw-head. To the arm F is pivoted one end of a foot, *k*, or otherwise 75 connected, so as to move on the arc of a circle lengthwise of the arm.

The foot *k*, which supports the arm F in an elevated position, rests at its lower end on a trip-lever, G, pivoted near its center to the 80 draw-head, its outer extremity having pivoted thereto a push-pin, *l*. This push-pin passes out through the front end of the draw-head, and when the coupling-pin E is held in an elevated position by means of the pivoted arm 85 F, foot *k*, and trip-lever G, as shown in Fig. 1, and the opposing draw-heads A B come together, the pin *l* will be forced in, and also the supporting-arms C. This will cause the trip-lever G to be pushed out from under the end 90 of the foot *k*, and the arm F dropping, carrying with it the pin E, and the foot also dropping into a mortise, *m*, in the draw-head, the pin E in its descent passing through the usual holes therefor and through the coupling-link D. 95

A spring, *n*, connected to the trip-lever G and passing through a staple, *o*, throws the lever back in position after the pressure is removed from the end of the pin *l*.

Having now fully described my invention, 100 what I claim as new, and desire to secure by Letters Patent, is—

1. In a car-coupling, the combination, with the draw-head formed with L-shaped slots at its sides and stops at their outer extremities, and the ends of the draw-heads having curved recesses therein, of curved supporting-bars connected together by a pin and elongated slot, and provided with shanks supported in eyes in the sides of the draw-head, and carrying keys working in the slots, substantially as 10 and for the purpose set forth.

2. In a car-coupling, a draw-head recessed at its end and provided with extensible supporting-arms for the coupling-link, and means for locking the arms in a closed position in

the recess, in combination with a coupling-¹⁵ pin, a pivoted arm, to which it is connected, a foot and a trip lever for supporting the arm, and a push-pin connected to the lever and extending out through the front end of the draw-head, substantially as and for the 20 purpose described.

In testimony that I claim the above I have hereunto subscribed my name in the presence of two witnesses.

JAMES M. EDWARDS.
